(57) CLAIM

I claim the ornamental design for headwear with cheese simulating members for sports fans, as shown and described.

DESCRIPTION

FIG. 1 is a front view of my new design for headwear.

FIG. 2 is a rear view of my headwear as shown in FIG. 1.

FIG. 3 is a top plan view of the headwear shown in FIG. 1.

FIG. 4 is a bottom view of the headwear shown in FIG. 1.

FIG. 5 is a side view of the headwear shown in FIG. 1.

FIG. 6 is an opposite edge view of the headwear shown in FIG. 1.

FIG. 7 is a fragmentary view of one of the headwear members shown from a viewpoint between the two members looking outward; and,

FIG. 8 is a fragmentary view of the other headwear member opposite to the one shown in FIG. 7, also shown from a viewpoint between the two members looking outward.
